UNITED STATES PATENT OFFICE.

GEORGE O. SANBORN, OF BOSTON, MASSACHUSETTS.

DESIGN FOR A PICKLE-BOTTLE.

SPECIFICATION forming part of Design No. 12,943, dated May 28, 1882.

Application filed April 15, 1882. Term of patent 7 years.

To all whom it may concern:

Be it known that I, GEORGE O. SANBORN, of Boston, in the county of Suffolk and State of Massachusetts, have invented and produced 5 a new and original Design for Pickle Bottles or Jars, of which the following is a specification, reference being had to the accompanying drawing, forming part thereof.

In the accompanying drawing the figure is 10 a side elevation of a bottle or jar made according to my design.

My design consists in forming the bottle A with its walls tapering more or less from the bottom to the top, somewhat in the manner of 15 an ordinary lamp-chimney. The mouth of the bottle is made large, and the neck gradually

widens to the body, which is about equal in diameter to the bottom.

The essential feature of the design is the cylindrical tapering form of the bottle, whereby 20 it is made to resemble a truncated lamp-chimney.

I claim—

The design for a pickle bottle or jar herein shown and described, which consists of the cylindrical walls gradually tapering from the bottom to the top. 25

GEORGE O. SANBORN.
